UNITED STATES PATENT OFFICE.

NATHANIEL L. BRADLEY, F. ROBERT SEIDENSTICKER, AND AUGUSTUS H. JONES, OF MERIDEN, CONNECTICUT, ASSIGNEES TO THE BRADLEY & HUBBARD MANUFACTURING COMPANY, OF SAME PLACE.

EXTENSION LAMP-FIXTURE.

SPECIFICATION forming part of Letters Patent No. 241,917, dated May 24, 1881.

Application filed February 23, 1881. (No model.)

To all whom it may concern:

Be it known that we, NATHANIEL L. BRADLEY, F. ROBERT SEIDENSTICKER, and AUGUSTUS H. JONES, of Meriden, in the county 5 of New Haven and State of Connecticut, have invented a new Improvement in Extension Lamp-Fixtures; and we do hereby declare the following, when taken in connection with the accompanying drawing, and the letters of reference marked thereon, to be a full, clear, and exact description of the same, and which said drawing constitutes part of this specification, and represents a sectional side view.

This invention relates to an improvement in 15 that class of lamp-fixtures which are designed to be suspended from the ceiling, and so that the lamp may be drawn down to stand at different elevations, commonly called "extension lamp-fixtures," and particularly to that class 20 in which the shade is supported on the lamp-supporting part of the fixture, so as at all times to stand in the same relation to the lamp; the object being to apply a frictional device operating against the downward movement of 25 the lamp, but relieved of such friction when the lamp is raised; and also to arrange a smoke-bell to move up and down with the lamp, so that it may always retain the same relative position to the lamp; and the invention consists 30 in the construction, as hereinafter described, and particularly recited in the claims.

A represents the frame on which the lamp is supported, commonly called the "harp." It is provided with a seat, B, at the center for 35 the lamp-fount, and with seats C C to support the shade D. The sides of the frame extend up through and above the shade, through the weight G, and come together, as at E, a distance above the shade sufficient for the support 40 of the smoke-bell in a proper relative position to the lamp, F representing the smoke-bell suspended from the connection E between the sides of the frame.

G represents the counterbalancing-weight, 45 in ring shape, above the shade, so as to permit the frame and smoke-bell to move up or down

through it, and from which chains or cords H extend up over pulleys above, thence down and attached to the lamp-frame, as shown, so that as the lamp is drawn down, as indicated in 50 broken lines, the smoke-bell moves with it and retains always its same relation to the lamp and shade.

As a means for producing friction to operate against the descent of the lamp, the pulleys I are provided with toothed ratchets a. Fixed pawls d are applied to the pulley-supports to engage the teeth of the ratchets, as shown, the direction of the teeth and action of the pawls being such that the pawls will hold 60 the ratchets and prevent the pulleys turning when the lamp is drawn down. Hence the chains will work over the pulleys while stationary, the friction between the chains and pulleys in such stationary condition aiding 65 materially in resisting the natural descent or counterbalancing the gravity of the lamp. Hence the weight G may be very much lighter than in fixtures where the pulleys are free to turn in both directions. When the lamp is 70 lifted—as for the purpose of raising it—the pulleys are free to roll without the applied friction, the weight aiding in the ascent of the fixture. Another advantage of the thus-applied friction is that whereas when the pulleys are 75 free to turn in both directions it is necessary that the weight should nearly counterbalance the fixture, and the adjustment between the weight and fixture is frequently so nice that if the fount be full the fixture will descend of its 80 own gravity, or if the oil be nearly exhausted the fixture will ascend because of the reduced weight, the applied friction, as by this construction, permits a much greater variation between the weight and fixture, and thus overcomes difficulties heretofore existing in this 85 class of fixtures.

We claim—

1. In an extension lamp-fixture, substantially such as described, the frame or harp, constructed to support the lamp, and with supports C for the lower edge of the shade, and 90

with extensions upward through the shade, said extensions connected above the shade, combined with the ring-shaped weight G, through which the extension of the frame moves up and down, substantially as described.

2. In an extension lamp-fixture, substantially such as described, the suspension-pulleys, provided with ratchet and pawl to hold the pulleys stationary against the descent of the lamp

and permit them to revolve when the lamp ascends, substantially as described.

NATHANIEL L. BRADLEY.
F. ROBERT SEIDENSTICKER.
AUGUSTUS H. JONES.
